RAM FOR CIRCUMFERENTIAL CRIMPING
 David Dibner, Wilton, Conn., assignor to Burndy Corporation, a corporation of New York
 Filed May 2, 1960, Ser. No. 26,379
 4 Claims. (Cl. 153—1)

This invention relates to the metal working art, and more particularly to the design of dies for the compression of malleable metal tubes on a central core.

It is commonplace to attach a malleable metal connector to a conductor by compressing the connector with the conductor inserted therein between a ram and a nest die to obtain a full circumferential crimp around the connector. It is difficult, however, to manufacture the ram and nest die to a close mating tolerance. Consequently, a flash is formed in the connector at the juncture of the ram and nest die about the connector.

It is, therefore, an object of this invention to provide a ram of novel design, which can be conveniently manufactured and will provide a very close fit between the nest die and ram at their juncture about the connector.

A feature of this invention is a pair of mating dies including a pair of projections disposed on the inner surface of one die adjacent the other die and adapted to project into said inner surface of said other die when said dies are closed.

These and other objects and features of this invention will become more apparent by reference to the following description taken in conjunction with the accompanying drawings, in which:

FIG. 1a is an end view in cross section of a ram and a nest die, in separated relationship, illustrating the prior art;

FIG. 1b is an end view in cross section of the ram and the nest die of FIG. 1a in closed relationship;

FIG. 2a is an end view in cross-section of a ram and a nest die, in separated relationship, embodying this invention;

FIG. 2b is an end view in cross section of the ram and the nest die of FIG. 2a in closed relationship;

FIG. 3a is an end view in cross-section of a pair of dies in separated relationship, illustrating an alternative embodiment of this invention; and

FIG. 3b is an end view in cross-section of the dies of FIG. 3a in closed relationship.

Referring now to FIG. 1a, the prior art arrangement is seen to consist of nest die 1 and a ram 2 which are adapted to circumferentially compress a connector 3. In mass production it is very difficult to produce a ram and nest die pair having a close fit, e.g.

+.000

-.001

therebetween. Consequently, when the circumferential crimp is made, as shown in FIG. 1b, the ram does not precisely mate with the nest die at their juncture about the connector, and a flash is formed at 4 and 5.

As will be seen in FIG. 2a, ram 21 includes a longitudinal slit 22 and a spring steel shield 23 mounted to the ram's working end by suitable means, such as the pinning of suitable tabs 24 and 25, to the bifurcation 26 and 27 created by the slit. The shield may be made with sharp edges 28 and 29, and being of spring steel, will conform to the width of the nest die 30, with the edges scraping the walls of the die. Thus when the connector 31 is circumferentially crimped, as shown in FIG. 2b, a very close fit will be obtained between the shield and the nest die, and no flash will be formed. The slit 22 permits the bifurcations to spread apart slightly when

2

the crimp is being made and to apply pressure to the edges 28 and 29 of the shield.

Referring now to FIG. 3a, a pair of abutting dies 41, 42 is here shown. One of the dies, as 42, has mounted therein a U shaped spring 43. The spring may be fastened to the die 42 by any convenient means to facilitate removal of a connector after crimping. For example, mechanical means such as integral tabs 24, 25 (shown in FIGURES 2a and 2b) or a suitable bonding agent applied between the spring and the die face, may be employed. When the dies are closed, the legs of the U are bent by the mating die, as 41. In the fully closed position, the ends of the U just abut each other, as shown in FIG. 3b. In operation the connector 44 is placed within the U spring 43 and the dies are closed. Spring 43 closes around the connector, preventing the formation of flash between the dies.

The invention has thus been described but it is desired to be understood that it is not confined to the particular forms or usages shown and described. The same being merely illustrative, and that the invention may be carried out in other ways without departing from the spirit of the invention, and therefore, the right is broadly claimed to employ all equivalent instrumentalities coming within the scope of the appended claims, and by means of which objects of this invention are attained and new results accomplished, as it is obvious that the particular embodiments herein shown and described are only some of the many that can be employed to obtain these objects and accomplish these results.

I claim:

1. A pair of mating dies for crimping a therebetween inserted connector; each of said dies having an inner surface forming a cavity including a pressure applying face; an arcuately formed leaf spring member mounted adjacent the face of one of said dies and having the distal ends thereof biased radially outward to resiliently bear against and slide along the other die inner surface, to obstruct the gap between adjacent surfaces of the dies as they are moved toward mating position; said leaf spring member being adapted to resiliently conform to the adjacent surface of the therein inserted connector as said dies are closed into full mating relationship and to resume its undeflected arcuate form when the dies are parted.

2. A pair of dies according to claim 1 wherein said leaf spring member is substantially U-shaped, the distal ends of the legs thereof being inwardly bent to facilitate flexure as the dies are closed.

3. A pair of dies according to claim 1 wherein the distal ends of the leaf spring member have beveled edges adapted to maintain smooth beveled contact with the inner surface of the other die as the dies are moved into full mating relationship.

4. A pair of dies according to claim 1 wherein one die is a ram and the other is a nest; said ram including a bifurcation in a plane including the longitudinal axis of the inserted connector for permitting slight spreading of said ram along said bifurcation when crimping the said connector.
